UNITED STATES PATENT OFFICE.

JOSEPH H. PRICE, OF LOMBARD, ILLINOIS, ASSIGNOR OF ONE-HALF TO CHICAGO PAPER COMPANY, OF CHICAGO, ILLINOIS, A CORPORATION OF ILLINOIS.

TYPOGRAPHICAL NUMBERING-MACHINE.

1,155,369.

Specification of Letters Patent.

Patented Oct. 5, 1915.

Application filed June 7, 1915. Serial No. 32,479.

To all whom it may concern:

Be it known that I, JOSEPH H. PRICE, a citizen of the United States, and resident of Lombard, in the county of DuPage and State of Illinois, have invented certain new and useful Improvements in Typographical Numbering-Machines, of which the following is a full, clear, and exact specification.

This invention relates to improvements in typographical numbering machines, the number wheels of which are sleeved on a shaft, and automatically advanced upon the successive movement of a plunger held against accidental movement by ratchets and swinging pawls moved to contact by a spring plate having fingers individual to each pawl and usually provided with what is called "drop-ciphers" to avoid printing non-significant ciphers in front of numbers.

Typographical numbering machines when assembled, as sold to a customer commonly contain five or six wheels, on the periphery of each of which, with the exception of the unit wheels, are numbers from one to and including a drop-cipher, and by their successive operation individually produce units, tens, hundreds, thousands and tens of thousands, and to do which the ciphers of every wheel are moved to a position dropping them below the surface of the numbers, so that in the commencement of the operation of the machine, the first imprinted number shall be one, and so on, as a strip of paper is exposed to the successive operations of their plunger. When, however, it is desirable or necessary to simultaneously imprint two or more numbers in their successive order, when there are two or more forms on the same page, as for example, bank checks, a separate numbering machine must be used for each form or check, and a skip-wheel substituted for the consecutive numbered unit wheel in every machine necessary therefor. That is to say, when there are two checks to the page, there must be substituted for the unit wheel of the first machine to operate a skip-wheel, with the numbers 1, 3, 5, 7 and 9, and on the second machine a skip-wheel having the numbers 0, 2, 4, 6 and 8, or in other words, on the wheel printing the unit "1," the numerals must be odd, whereas on the wheel printing the first unit "2," the numerals must be even. Again for printing numbers in their consecutive order on a

sheet for three bank checks, three numbering machines must be employed, and each provided with a skip wheel, with the numbers on the unit wheel of the first machine, beginning with "1," consecutively followed by the numbers 4, 7, 0, 3, 6, 9, 2, 5 and 8, and on the unit wheel of the second machine, beginning with 2, followed in order with 5, 8, 1, 4, 7, 0, 3, 6 and 9, and on the unit wheel of the third machine beginning with 3, and followed in order with 6, 9, 2, 5, 8, 1, 4, 7 and 0.

With the numbers arranged on the skip-wheels and in the order above described, there will be simultaneously printed "1" on the first check of a sheet by the unit wheel of the first machine, "2" on the next check by the unit wheel of the second machine, and "3" on the next and third check by the unit wheel of the third machine, and on the second sheet in like manner, "4" by the unit wheel of the first machine, "5" by the unit wheel of the second machine, and "6" by the unit wheel of the third machine, and so on, until all of the sheets for a three check bank book are successively numbered, or until the capacity of the three machines is exhausted, and whereupon they are reset to commence in like manner with the numeral "1," as before.

For consecutively numbering five forms or checks to a sheet, five machines must be simultaneously used and operated with a skip-wheel for each, with their numbers varying accordingly as above indicated, and in which event with the cipher omitted from the last wheel of the series, the highest number printed will be 999,999.

In the construction of variously numbered strips, as for example bank checks, it is the practice to first print the blank form of the checks and subsequently apply the numbers thereto in their consecutive order, and which is and may be done with a single machine, when the checks are to be subsequently bound with one check to the page, without the use of a skip-wheel, that is to say when the unit wheel contains in their order the numerals 1 to a cipher inclusive, and as such numbering machines are commonly assembled, and sold. When a sheet contains two or more checks, or other printed forms to be numbered consecutively throughout a number of such sheets, the

use of a skip-wheel whereby the two or more checks on a sheet may be simultaneously numbered consecutively and likewise of the following sheets in their passage through the printing press either after or simultaneously with the printing of the three separate forms thereon is desirable as a saving in time and expense for having them consecutively numbered. But heretofore, there has been a serious objection to the use of skip-wheels because of the difficulty of substituting a skip-wheel for a unit wheel in order to simultaneously consecutively number two or more checks or other blanks to the sheet, and vice versa for numbering consecutively but one blank to a sheet. In other words, before my invention, so far as I am aware, there has been no typographical numbering machine, wherein it is possible or practical to substitute a skip-wheel for an ordinary unit wheel without removing all of the other numbering wheels from a fixed shaft upon which they are free to revolve, and disconnecting them from their spring actuated pawls, and this after first removing the plunger and the rocking arm through which the several numbering wheels must be and are operated, and for the reason that their shaft is only removable through the ends of the machine opposite that occupied by the plunger. Indeed so far as I am aware there was prior to my invention, no successful typographical numbering machine on the market wherein it is possible to substitute a skip-wheel for the ordinary unit wheel, or vice versa, without dismembering the machine as above described, or which after being dismembered can be reassembled by the ordinary purchaser, or even by a skilled mechanician outside of the factory where they are made, in less than about an hour, and a half an hour at best, and even then only by great care, skill and patience. From the foregoing it will now be apparent that any means by which it is possible and practical for anyone of ordinary intelligence and without the skill of a mechanician to substitute in a typographical numbering machine, a skip-wheel for the unit wheel and vice versa without disassembling any of the parts of such a machine, and without any liability to do so will be a marked improvement in the art.

The prime object of my invention, broadly stated, is to provide a typographical numbering machine with a shaft for and about which the numbering wheels are free to revolve, the construction of which shaft is such that a skip-wheel may be substituted for the ordinary unit wheel, and vice versa without disassembling the machine, or moving or removing the shaft in its entirety, or disturbing any of the numbering wheels other than that of the substitution.

More specifically stated, the object of my

invention is to provide a typographical numbering machine with a shaft fixed and supporting the several numbering wheels as usual formed in two lengths, or transverse sections, one of which is socketed and adapted to be interlocked with the other, and form the sole support for either a unit or skip-wheel as may be, one of which sections is fixed in its operative position by the use of a single set screw, and is adapted to be detachable from the other section, and removed away from the unit wheel or skip-wheel as may be, and outwardly through the end of the machine adjacent said unit or skip-wheel on retracting the impinging set screw therefrom, and whereby a skip-wheel or a unit wheel may be substituted the one for the other without disassembling or removing any of the remaining wheels from the shaft.

Another object of my invention is to provide a typographical numbering machine having a sectional shaft adapted to support the several numbering wheels thereof provided with a simple and effective means for visually indicating externally of the working parts thereof the position to which the shaft must be turned before being tightened, that it must have for the ciphers of the several wheels to drop below their operative position into the groove provided therefor.

With these ends in view, my invention finds embodiment in certain features of novelty in the construction, combination and arrangement of parts by which the said objects and certain other objects are attained, all as hereinafter fully described with reference to the accompanying drawings, and more particularly pointed out in the claims.

In said drawing, Figure 1 is a top plan view of a typographical numbering machine in which my invention finds embodiment, but containing the usual unit wheel instead of a skip-wheel, to be referred to. Fig. 2 is an elevation of one end thereof adjacent the plunger. Fig. 3 is an end elevation of the opposite end of the machine showing the removable section of the shaft. Fig. 4 is a longitudinal section taken on the line 4—4 of Fig. 1. Fig. 5 is an end elevation with the plunger removed to expose the rocker arm and the adjacent end of the shaft upon which the numbering wheels are mounted. Fig. 6 is an end elevation of the female member of the sectional shaft. Fig. 7 is a similar view of the male member of the sectional shaft, and Fig. 8 is a detail longitudinal section through the shaft for more clearly showing the arrangement of the shaft locking lugs relative to the groove for receiving the drop-ciphers of the numbering wheels.

Similar characters of reference indicate the same parts in the several figures of the drawing.

The frame of the machine as usual con-

sists of end walls 9 and 10 connected by means of bars 11, at each side thereof spaced apart, the wall 9 being provided with outwardly projecting parallel flanges 12—12 5 projecting between which and suitably locked thereto is a plunger 13 by means of a U-shaped plate 14 from which is bent a bottom piece 15 supporting a coiled spring 16 yieldingly supporting the plunger above 10 its operative position for actuating a rocking arm 17.

Rocking arm 17, as shown in the drawings, is supported free to turn on the reduced end 18 of a shaft 19, and is actuated by the 15 plunger and connected with a series of numbering wheels in any ordinary and usual manner.

Mounted and free to turn upon the shaft 19 is a series of numbering wheels which 20 in the order of their arrangement consist of a ten thousand's wheel 20, thousand's wheel 21, hundred's wheel 22, a ten's wheel 23 and a unit wheel 24, each of which wheels as shown in the drawings, are peripherally 25 provided with raised or typographical numbers consecutively thereon from "1" to and including a cipher, each of which wheels is provided with a circular rack 25 depressed below the face of the numerals engaged by 30 as many pawls 26, moved to contact with their respective circular racks by means of as many spring tongues 27, secured to the side bar 11 of the frame, by means of set-screws 28.

35 At the opposite side of, well toward the bottom of the wheels (see Fig. 4) are a series of stops 29, one for each wheel, adapted to project into opposing recesses 30, for yieldingly holding the numbering wheels 40 from accidental movement, and to which end the stops are pivoted on a shaft or rod projecting at each end into a yoke 31 provided with opposing upright arms 32—32, sleeved upon the shaft 19 adjacent the end walls 9 45 and 10 of the frame.

As before stated every numbering wheel save the ten thousand's wheel is provided with a cipher, which is useless on the last to be operated of the several wheels, and as 50 indicated by the groove 33 in the shaft 19, all of these ciphers are drop-ciphers, that is to say are formed separate from the wheels, and confined in slots therein so that the structure upon which they are formed may 55 drop into the groove and to a plane below their printing position.

With the exception of the construction and arrangement of the shaft as hereinafter described, it will now be observed that otherwise 60 the typographical numbering machine shown in the drawing, is identical in construction and operation with one of several types of numbering machines heretofore upon the market and now extensively 65 in use the shafts of which, however, for sup-

porting the numbering wheels are without exception made of one piece, supported at their opposite ends in the frame and maintained against movement by means of a set-screw 34 passing through the top of one end 70 of the piece and impinging against their shaft as shown in Fig. 4 of the drawings.

The use of a one piece shaft in the several types of numbering machines now upon the market wherein it is possible to make the 75 substitution of a skip-wheel for a unit wheel, and vice versa, of necessity requires for the substitution of a skip-wheel for a unit wheel and vice versa, the disassembling of the machine in its entirety, and for which purpose the plunger must first be removed from the machine, followed by removing the rocking arm from the shaft, then withdrawing the shaft outwardly through the frame in the opposite direction until all of the 80 numbering wheels are removed therefrom, before the substitution can be made of a skip-wheel for the unit wheel, or vice versa. With the removal of the numbering wheels, the pawls 26 being loose upon their shaft, 85 swing inwardly by gravity and must be held in their operative position while pushing the shaft through the several numbering wheels for restoring them to their operative position, and for which purpose their opposing springs must be detached from the frame.

The difficulty and skill required to reassemble typographical numbering machines will, however, be better appreciated on bearing in mind that the depth and width of their frame as they are sold upon the market is less than three-quarters of an inch, with a total length of but one and seven-eighths inches, with the diameter of their wheels 90 barely three-quarters of an inch, with their springs and pawls correspondingly small, and so small that they can only be successfully reassembled with the use of the fingers and a pair of pincers, and as a result of which, and 95 only from frequent practice can even a skilled mechanic reassemble them with an expenditure of at least thirty minutes if not more of time. Indeed the difficulty and expense for reassembling typographical numbering machines, has heretofore been so great that, notwithstanding the advantages to printers from the use of skip-wheels, but few and only very large printing establishments can 100 be persuaded to use them.

110 From the foregoing it will now be apparent that any means which for the first time makes it both possible and practical to substitute skip-wheels for unit wheels and vice versa in typographical numbering machines, without disturbing any of the other numbering wheels, or the mechanism therein for operating them, and especially if such substitution may be made without the aid 115 of mechanical skill, and by a boy, with the 120 125 130

expenditure of not more than two or three minutes of time, and whereby the use of skip-wheels at once becomes available to everyone using typographical numbering machines.

From many years of experience in the use of several of the different styles of numbering machines on the market, and repeated efforts to devise some means by which skip-wheels might be successfully used without the necessity of disassembling the entire machine, I have finally discovered that this may be done without changes in their mechanism other than dividing their single shaft 10 in two inter-locking sections; one section of which supports no numbering wheel other than the unit or the skip-wheel as may be, and is removable partly or wholly away from the other section, and from the machine 15 through the end wall thereof adjacent such skip or unit wheel. For example, as shown in Fig. 4, the single piece shaft heretofore provided as a support for the numbering wheels is transversely divided on a line in a plane with the inner surface of the unit wheel 24, and the adjacent surface of the ten's wheel 23, one section of which 20 forms the support for the several numbering wheels 21, 22 and 23, and the other section 25 36 a support only for the unit wheel 24, the adjacent ends of which sections are provided with interlocking means whereby they may both be held against turning by means of the screw 34 heretofore employed 30 for the same purpose.

As shown in the drawings the locking means consists in providing the end of the section 35 with a socket 37, and opposing radial grooves 38 respectively adapted to receive a pin 39 and lugs 40 and 41 projecting from the opposing end of the section 36, whereby when the two sections are in their operative interlocked position, both sections may be held against turning by the 45 single screw 34 to impinge therewith.

With this construction of the shaft, it will be seen that for substituting for the unit wheel 24 a skip-wheel this may be quickly done by loosening the screw followed by drawing the shaft section 36 away from the shaft section 35, until the section 50 36 is free and clear of the unit wheel 24, which may then be easily removed by the fingers, and a skip-wheel therefor be substituted by first holding it in register with the section 36, followed by moving the shaft section 36 therethrough to locked engagement with the section 35, and then tightening the set-screw 34.

As a means for visually determining when the groove 33 of the shaft registers with the drop ciphers, and how much the shaft must be turned to move the groove into register before tightening the shaft with 60 the set screw, it will now be observed that

the lug 40 and the socket therefor is wider than that of and for the lug 41, and that these lugs are arranged on a line at a right angle to the groove, and that furthermore the outer end of the shaft is provided with 70 a notch 42 in line with the lug 40, so that on turning the shaft until this notch 42 meets the right hand end of a horizontal line at a right angle to the length of the groove, the operator will then know that the 75 groove is uppermost and in register with the drop ciphers. The form of the notch 42 is such that it provides a means for the engagement of a hook for pulling the shaft section 36 outwardly or for a screw-driver 80 projected into the end groove 43 of the section 36 for turning the shaft as and for the purposes before described.

My invention as providing a means for the substitution of a skip wheel for a unit 85 wheel without disturbing the other wheels of a typographical numbering machine, is not to be limited to the special form of devices for connecting, locking and indicating the point to which the shaft shall be 90 turned for registering the drop ciphers with the groove therein, but includes any other form adapted for the purposes thereof.

Having described my invention, what I claim and desire to secure by Letters Patent is:

1. A typographical numbering machine comprising in combination a plurality of numbering wheels, a sectional shaft for supporting said wheels, one section of which 100 supports the unit wheel to the exclusion of the other wheel and wheels.

2. A typographical numbering machine comprising in combination a series of numbering wheels, a transversely divided shaft 105 therefor, means for removably locking the sections thereof together, and a unit wheel supported upon one of said sections to the exclusion of the other numbering wheels.

3. A typographical numbering machine 110 comprising in combination a series of numbering wheels, a sectional shaft transversely divided into two sections, a pin on one section, a socket in the other section for receiving said pin, means for preventing the rotary movement of either section, and means for maintaining said shaft against longitudinal movement.

4. A typographical numbering machine comprising in combination a series of numbering wheels, provided with drop ciphers, a shaft for supporting said wheels, provided with a groove adapted to receive and maintain said ciphers in their dropped position, said shaft being constructed in sections removably jointed together, one of which sections is provided with means for visually indicating when the groove therein is in register with the drop ciphers.

5. A typographical numbering machine 130

comprising in combination a sectional shaft, provided with a longitudinal groove, a series of numbering wheels mounted upon said shaft, provided with drop ciphers adapted to be moved to register with said ciphers on turning the shaft, means whereby both sections of said shaft may be simultaneously revolved, means for indicating the register of the drop groove with the ciphers there-

for, and means for locking said shaft in a fixed position.

In witness whereof, I have hereunto set my hand and affixed my seal, this 1st day of June, A. D. 1915.
